UNITED STATES PATENT OFFICE.

FRANK ALBERT STUMM, OF NEW YORK, N. Y.

TELEGRAPH.

SPECIFICATION forming part of Letters Patent No. 781,752, dated February 7, 1905.

Application filed December 4, 1902. Serial No. 133,883.

To all whom it may concern:

Be it known that I, FRANK ALBERT STUMM, a citizen of the United States, and a resident of the city of New York, borough of Manhattan, in the county and State of New York, have invented a new and Improved Telegraph, of which the following is a full, clear, and exact description.

My invention relates to telegraphy, and more particularly to provision against the disturbing effects due to wet weather upon lines using the duplex, quadruplex, and other systems in which the line is required to be kept approximately in "balance."

My invention rests upon the discovery that by inserting a suitable artificial resistance in the main-line circuit between the relay and the line-wire proper the working of the line is greatly improved—so much so that the capacity for transmitting messages may be greatly increased above what it would otherwise be in wet weather.

It may be remarked that in telegraphic systems of the kind above mentioned the resistance of the line must be kept in balance, which is done by interposing a variable resistance in the so-called "equating-circuit"—that is to say, in every such system it is necessary to vary the resistance of the equating-circuit in order to bring the lines into balance in all cases where the main-line wire is subject to leakage or analogous disturbing causes.

Reference is to be had to the accompanying drawing, forming a part of this specification, in which the figure is a diagrammatic representation of my system as applied to an ordinary duplex telegraph.

The main-line wire is shown at 1. At each end of the line-wire are disposed variable resistances consisting of switches 2 3, which may be moved by hand at will over the rheostatic connections 4 5. Polarized relays 6 7 of the usual pattern are provided with oppositely-wound poles 8 9. A wire 10 from one of the poles 9 is connected with the resistance 11, controllable by means of a hand-switch 12, this switch being connected by a wire 13 with the wire 15, which leads to the normal contact 14 and to the ground-wire 16.

Branch wires 17 18 are connected with the wire 19, which leads to the key 20, this key being provided with an abnormal contact 21 in the usual manner. The line may be energized by a battery 22 and is grounded at 23. At the other end of the line the arrangement is similar, the wire 24 being connected with the resistance 25, controllable by the switch-arm 26, this switch-arm being connected by wires 27 and 29 with the normal contact 28 and with the ground-wire 30. Branch wires 31 32 are connected with the relay 7 and with the wire 33, which leads to the key 34, this key having an abnormal contact 35 connected directly with the ground-wire 30. A battery 36 is inserted in the circuit at this end of the line. This battery is inserted in the wire 30, which is grounded at 37. If desired, dynamos 38 39, provided with cut-out switches 40 41, may be employed instead of the batteries 22 and 36. For this purpose cut-out switches 42 and 43 are provided, so as to throw the batteries out of circuit when the dynamos are to be used.

My invention is used as follows: Suppose, for instance, that the normal resistance of the main line in dry weather is two thousand ohms and that because of wet weather the ohmic resistance of the main line is dropped to a certain unknown degree. The operators by means of the hand-switches 12 or 26 adjust the resistances 11 or 25 to such a point that the line balances. In other words, as in ordinary systems, each operator brings the line to a balance by varying the resistance of the so-called "equating-circuit" and notes the change in resistance necessary to accomplish this result. Say, for instance, that the resistance of the main line is found to be one thousand ohms instead of the normal resistance of two thousand ohms above mentioned. The falling off in the resistance is clearly one thousand ohms. The operator next adjusts one of the hand-switches 2 or 3, so as to cut into the main line a resistance equal to, say, fifty per cent. of the difference just ascertained. He therefore cuts in five hundred ohms. Each operator now moves his hand-switch 12 or 26 and again balances the line.

Of course the resistance of the line is now greater than before, and when the line is thus balanced for the second time it is ready for use and the operation of telegraphy may proceed. Of course the hand-switches 2 or 3 are moved to the zero-point when the first balance is taken and are at some other point when the second balance is taken. The principle appears to be that by the introduction 10 of the rheostatic members 4 and 5 the current passing through the main line is less subject to fluctuations or disturbances than would be the case if no such resistances were introduced. In other words, with a considerable 15 current flowing through the main line and resistances connected therewith the variations are not nearly so noticeable, and the effect is practically the same as if the points of leakage were moved farther away from the 20 relay, so that their effect is not so marked.

While the degree of resistance which I prefer to introduce into the main-line resistances is fifty per cent. of that found by a difference between the normal main-line resistance and 25 the resistance during wet weather and is found by balancing the line by means of the equating-circuit, yet this particular proportion is in a sense arbitrary, and I do not, therefore, limit myself to any particular percentage. I have found from experience that fifty 30 per cent. gives a very satisfactory result.

The adjustment of the line under my system may therefore be summarized as follows: First, balance the line by means of the equating-circuit and find the loss in resistance of 35 the main line; second, add to the main line an artificial resistance representing one-half of that thus ascertained; third, let this resistance stay in the main line and balance the main 40 line by means of the equating-circuit. The line is then ready to be used.

The operation of the system is practically the same whether dynamos or batteries are used; but allowance should be made for the fact 45 that with dynamos the internal resistance is practically nothing; but with batteries the internal or cell resistance may be very great.

It will be understood, of course, that the equating-circuit mentioned herein is either the 50 one consisting of the wire 10, rheostatic member 11, wire 13, and ground or the one consisting of wire 24, rheostatic member 25, wire 27, and ground.

Having thus described my invention, I claim 55 as new and desire to secure by Letters Patent—

1. The method, herein described, of ameliorating current fluctuations in balanced lines used for purposes of communication, which consists in determining the mean variation of 60 the main circuit from a predetermined normal, increasing the resistance of the main-line circuit to an extent proportionate to the varia-

tion thus determined, and balancing the main-line circuit with its resistance thus increased.

2. The method, herein described, of ameliorating 65 current fluctuations in balanced lines used for purposes of communication, which consists in taking a balance of the main-line circuit, thereby determining the mean variation in the current thereof from a predetermined normal, increasing the resistance of the main-line circuit to an extent proportionate to the mean variation thus determined, and again balancing the main circuit with its resistance thus increased.

3. The method herein described of ameliorating 70 current fluctuations in balanced lines used for purposes of communication, which consists in determining the mean variation of the current of the main-line circuit from a predetermined normal, changing the resistance of the main-line circuit to the extent of approximately fifty per cent. of the variation thus determined, and then balancing the main-line circuit.

4. The method herein described of ameliorating 75 current fluctuations in balanced lines used for purposes of communication, which consists in taking a balance of the main-line circuit, changing the resistance of the main-line circuit and taking a second balance of said main-line circuit.

5. The method herein described of ameliorating 80 current losses in balanced lines used for purposes of communication, which consists in balancing the line, thereby determining the main variation of the resistance of the main-line circuit below a predetermined normal, adding to the resistance of the main-line circuit a resistance equal to approximately fifty 85 per cent. of the loss thus ascertained, and finally taking a new balance of the main-line circuit.

6. The method herein described of ameliorating 90 current fluctuations in balanced lines used for purposes of communication, which consists in ascertaining the normal resistance of the main-line circuit, balancing the line to detect and determine any loss in the observed 95 resistance of said main-line circuit as compared with the normal resistance thereof, adding to said observed resistance of said main-line circuit a resistance approximating one-half of the loss in the resistance thus ascertained, and finally balancing said main-line circuit including 100 said resistance thus added thereto.

In testimony whereof I have signed my name to this specification in the presence of two subscribing witnesses.

FRANK ALBERT STUMM.
